UNITED STATES PATENT OFFICE.

WILLIAM S. WELLS, OF BETHLEHEM, PENNSYLVANIA, ASSIGNOR TO JOHNS-MANVILLE, INCORPORATED, A CORPORATION OF NEW YORK.

SPRING-TENSION CREEL.

Application filed October 26, 1922. Serial No. 596,947.

To all whom it may concern:

Be it known that I, WILLIAM S. WELLS, a citizen of the United States of America, residing at Bethlehem, in the county of 5 Northampton and State of Pennsylvania, have invented certain new and useful Improvements in Spring-Tension Creels, of which the following is a specification.

My invention relates to looms generally 10 but is more specifically designed to produce a spring tension creel for use in looms weaving cloth or bands containing fifty per cent or more of asbestos thread or yarn. Such asbestos thread or yarn has little or no 15 elasticity and to secure even weaving and avoid the breaking of thread or yarn, it is important that the tension on each thread shall be accurately adjusted and the tension support highly elastic and at the same time 20 the respective threads be kept out of contact one with another until they are actually combined in the weaving operation.

My invention is designed to secure these 25 desired results to a high degree and the best form of apparatus embodying the principles thereof at present known to me, is illustrated in the accompanying three sheets of drawings in which—

Fig. 1 is a plan view of the creel, with 30 parts broken away;

Fig. 2 an end view thereof, with parts shown in section and others removed; and

Fig. 3 is a side elevation with parts broken away, including a portion of the loom 35 harness.

Throughout the drawings like reference characters indicate like parts.

1 represents the supporting frame of the creel in which are mounted the bobbin support journal bearings 2, and the sheave 40 supporting posts 9. In each bobbin supporting journal is mounted a bobbin or spool support comprising a vertical spindle 3, and a horizontal circular flange 4, said spindle 45 having a stepped ball bearing 5. 6 represents the spool or bobbin mounted on the bobbin support and rendered revolvable therewith by means of the pin 21, set in the flange 4 and engaging a recess in the bottom 50 of the spool (not shown). 7, 7, represent the warp threads which are unwound from their respective spools 6, 6, and pass first over the fixed guide-sheaves 8, thence over a spring-supported guide-sheave 11, and finally over 55 a second fixed guide-sheave 10, from which

latter the threads pass over the warp bearing 17 to the heddles 18 and 19 of the harness, each vertically reciprocated in guides 20 by the usual mechanism, not shown.

The fixed guide-sheaves 8 are journaled 60 on horizontally extending rods 15, which are preferably supported by being held by nuts to the vertical central strip 16, which is perforated to receive them. The said strip 16 is clamped at either end to the posts 9, 65 and the above described method of mounting these sheave-supports 15 in strip 16, renders the sheaves adjustable in a horizontal plane toward and from the central strip 16, if desired. 70

As shown, the fixed guide-sheaves 8 revolve in a vertical plane while the other fixed guide-sheaves 10 revolve in a substantially horizontal plane.

Each yielding tension sheave 11 is supported upon one end of a flat spring 12, the other end of which is set in a rigid support, preferably formed integral with the journal block 2 of the bobbin-supporting spindle and consisting of the slot 14, in 80 which the extreme end of the spring 12 rests, and the adjustable tension screw 13 which passes through a perforation in the spring 12 and is threaded into a socket in the journal block 2. 85

As shown, the portion of the spring 12 intermediate between the end on which the sheave 11 is journaled and the point at which the adjusting screw 13 passes through it, normally bears upon the circumference 90 of the flange 4 on the bobbin support.

The horizontal guide sheaves 10, as shown, are mounted in a plane approximately horizontal, which plane passes through the heddles, but are set in lines slightly inclined to 95 the path of the warp threads passing to said heddles, with the result that said warp threads are evenly spaced one from another and preserved from contact one with another until they have passed through the heddles 100 to the weaving apparatus proper. In operation the spring 12 yields slightly each time the warp is pulled forward and readily adjusts itself so as to preserve a uniform tension on the thread whether or not the same 105 is pulled forward to a greater or less extent by the action of the loom. At the same time that the tension sheave is pulled forward by the thread, the friction of the spring 12 on the circumference of the bobbin support 110

flange 4, is relieved more or less and thus any excess draft on the warp thread creates a lessening of resistance to the unwinding of the thread from the bobbin or spool 6, 5 and this also assists in maintaining a uniform tension on the thread independently of the rapidity with which it is unwound from the bobbin.

By the use of my invention a close and 10 even fabric can be woven of asbestos threads or threads of both asbestos and other fibre and with little or no breakage of the asbestos thread or yarn.

Various changes can be made in the 15 details of the construction illustrated and described, without departing from the principle of my invention, so long as the general arrangement of the parts and method of operation above described are retained in 20 substance.

It is evident that the loose mounting of 25 spring 12 allows the spring supported tension sheave 11 to swing slightly sideways, in addition to its spring motion forward and backward and upward and downward. As a result said tension sheave is capable of limited motion in all directions.

Having described my invention, I claim:

1. In a spring tension creel for looms the 30 combination of a series of bobbin supports for the warp threads, a series of spring-supported guide sheaves, one for each bobbin, the springs for supporting said guide sheaves being capable of limited movement in 35 all directions, sets of two corresponding guide sheaves lying and being mounted to rotate in planes inclined one to the other over one of which sheaves the warp thread from each

bobbin passes in going to the spring-supported sheave and over the other of which it 40 passes after leaving the spring-supported sheave, the spring-supported sheave being located outside of the straight line connecting said two guide sheaves.

2. The combination with a circular rev- 45 oluble bobbin support for a thread and guide sheaves for said thread, of a yielding tension sheave located at a point intermediate of the two first mentioned sheaves, said tension sheave being mounted on one end of a flat spring, the other end of which is set in a fixed support, and an intermediate portion of which normally bears on the circumference of the bobbin support.

3. An apparatus such as set forth in claim 55 2, in which the fixed support for the spring comprises an adjustable member by which its normal friction on the bobbin support may be varied.

4. An apparatus such as set forth in claim 60 3 in which the bobbin support is carried by a vertical spindle having a ball forming its step bearing.

5. The combination, with a series of sup- 65 ports on which bobbins for the warp threads may be revolvably mounted, and a series of spring tension sheaves, one for each warp thread, of a series of fixed guide sheaves over one of which each thread passes after 70 leaving its spring tension sheave, said fixed sheaves being mounted all in a plane passing through the heddles of the loom and on lines slightly inclined to the path taken by the threads on their passage to said heddles.

WILLIAM S. WELLS.
